UNITED STATES PATENT OFFICE.

JENNINGS E. FOGLE, OF BROWNSVILLE, OREGON, ASSIGNOR OF ONE-SIXTH TO FRANK LIGHT, OF SALEM, OREGON, ONE-SIXTH TO JOHN DEWAYNE DENSMORE, OF SCIO, OREGON, AND ONE-SIXTH TO PAUL G. KOPPLIN, OF SHEDDS, OREGON.

RAILROAD-RAIL HOLDER.

1,187,296.

Specification of Letters Patent. Patented June 13, 1916.

Application filed October 26, 1915. Serial No. 58,011.

To all whom it may concern:

Be it known that I, JENNINGS E. FOGLE, a citizen of the United States, residing at Brownsville, in the county of Linn and State 5 of Oregon, have invented certain new and useful Improvements in Railroad-Rail Holders, of which the following is a specification, reference being had therein to the accompanying drawing.

10 This invention relates to railroad rail holders, and has for its principal object the production of a simple and efficient means for retaining the rails in their correct positions upon the ties.

15 Another object of this invention is the production of a railroad rail holder wherein a base plate is provided which is adapted to be positioned upon a tie, after which the tread plates which engage the rails are then 20 positioned upon the base plate so as to be positively retained in their correct set positions upon the base plate, so that when the rail is positioned in engagement therewith it will be retained permanently in its correct 25 position.

Another object of this invention is the production of a railroad rail holder wherein the tread plates and base plate are so constructed as to allow the tread plates to be 30 interchangeable for accommodating various sized rails, these plates being provided with simple and efficient means for positively retaining the same in set positions when assembled.

35 With these and other objects in view this invention consists of certain novel combinations, constructions, and arrangements of parts as will be hereinafter fully described and claimed.

40 In the accompanying drawings: Figure 1 is a side elevation of the railroad rail holder illustrating the same in use. Fig. 2 is an end elevation of the device as constructed in accordance with this invention, a rail being 45 shown in section. Fig. 3 is a section taken on the line 3—3 of Fig. 1, looking in the direction of the arrows. Fig. 4 is a top plan view of the railroad rail holder, the rail being removed. Fig. 5 is a detailed perspective view of the base plate. Fig. 6 is a sectional view taken on the line 6—6 of Fig. 4, looking in the direction of the arrows. Fig. 7 is a detailed perspective view of one of the tread plates. Fig. 8 is an enlarged frag-

mentary sectional view of a portion of the 55 base plate, illustrating the manner in which the spurs dig into the tie. Fig. 9 is a section taken on the line 9—9 of Fig. 8. Fig. 10 is a transverse section through the device shown in assembled position, and showing 60 the manner in which the tread plates may be interchanged. Fig. 11 is a plan view of a slightly modified form of the base plate.

Referring to the accompanying drawings by numerals it will be seen that the railroad 65 rail holder comprises a base member 1, which is preferably rectangular, as clearly shown in Fig. 5. This base plate 1 is provided adjacent its corners with the spike openings 2, the portion of the metal which is struck 70 from these openings being bent downwardly to provide or constitute the spurs 3. These spurs 3 are provided with pointed lower ends 4, facilitating their insertion into the ties when the device is being assembled. It 75 is intended that the spurs 3 when struck from the plate 1 are each to extend at right angles to the two adjacent spurs so that the side edges of the spurs will resist any tendency of the movement of the plate in one 80 direction, as will the broad bearing surface of the two remaining spurs. This plate 1 is further provided with a pair of parallel elongated slots 5 formed at a distance from each other, thereby forming a reinforcing 85 strip 6. Another slot 7 is formed at right angles to the slots 5 intersecting the same at their central portions.

The tread plates are similarly constructed, and it is thought, therefore, that the 90 description of one tread plate will be sufficient for disclosing the construction of both. Therefore, by referring to Fig. 7 it will be seen that each tread plate comprises an elongated body 8 having the upwardly extending rail engaging flanges 9 and 10 formed upon one side portion thereof. These flanges 9 and 10 are spaced apart so as to provide the open portion 11 for purposes to be hereinafter set forth. Upon 100 the opposite side of the plate 8 there are provided the anchor flanges 12 which depend below the lower surface of the plate 8 and are formed to provide an open space 13 therebetween. When this device is in 105 use the plates are positioned upon the ties so as to allow one plate to be positioned adjacent each end of the tie beneath the rail

extending thereacross. As the plate is positioned upon the tie it is easily driven so as to cause the spurs 3 to pierce the tie 14, since the pointed ends 4 of the spurs will penetrate the tie, as shown very clearly in Figs. 8 and 9. As hereinbefore stated, each plate is provided with four spurs, and as these spurs extend at right angles relative to each other strain will be very much reduced upon any one spur, since all of the spurs are constructed so as to take up the strain, and two of the spurs will take up the strain upon their side edges and will thus be prevented from being bent from their position independent of secondary securing means. Two tread plates being positioned upon the base plate, as clearly shown in Fig. 4. When a rail, as shown at 15, having a broad lower portion 16 is positioned upon the tread plates the rail engaging flanges 9 and 10 of the tread plates will engage the side surface of the lower portion 16 of the rail. At this time the anchor flanges 12 depending from the plate 8 will extend into the parallel slots 5 formed in the base plate, as shown in Fig. 3, and thus it will be seen that the tread plates 8 will be efficiently retained from creeping or slipping upon the base plate 1. It is, of course, obvious that the tread plates are first positioned upon the base plate by passing the anchor flanges 12 into the slots 5 before the rail is positioned thereon. After the rail is positioned upon these tread plates it will be seen that they will be positively held from accidentally jumping from engagement with the base plate so as to allow the rail 15 to become loose. After the rail has been positioned upon the tread plates, the spikes 17 may be passed through the openings 2 formed in the base plate 1, and driven into the tie 14. It will be seen that the heads 18 of the spikes 17 will engage the base or lower portion 16 of the rail 15 and will positively anchor the rail in engagement with the tread plates 8. It will be noted by referring particularly to Fig. 4 that only two of the openings 2 are exposed, so that after the tread plates 8 have been positioned upon the base plate 1, and the rail 15 placed upon these tread plates only two spikes are required for positively anchoring these elements in engagement with each other. Furthermore it will be seen that the openings 2 are constructed or formed within the base plate 1 so as to be in direct alignment for registering with the open space 11 formed between the rail engaging flanges 9 and 10 of the plates 8. It will be seen that by providing the reinforcing strip 6 any tendency of the anchor flanges 12 to move toward each other is eliminated, as these anchor flanges will fit snugly within the slots 5, as shown clearly in Fig. 3.

When a rail 15' having a narrow or reduced base or lower portion 16' is used the base plate is borne fixedly in the manner shown in Figs. 1 to 4 inclusive, so as to allow the slots 7 to extend longitudinally 70 of the tie upon which the plate is carried. This slot is considerably wider than the slots 5, so that when the tread plates 8 are positioned upon the base plate 1 the anchor flanges 12 may be passed into the slot 7, 75 as shown in Fig. 10, as sufficient space is provided to accommodate the two flanges at one time. The rail may then be positioned upon the tread plates, while the flanges 9 and 10 will anchor the same in its 80 correct position as hereinbefore set forth. At this time the spikes 17 may be passed through the unobstructed openings 2 as hereinbefore set forth, for anchoring the several elements in their correct engagement with each other. In other respects the device as disclosed in Fig. 10 operates similarly to the manner in which it operates as above set forth. It is simply intended to provide the base plate with an 85 additional slot 7, so that when rails having narrow lower or base portions are used, the base plate may be shifted so as to hold the tread plates adjacent each other, thereby providing the correct space between the 90 rail engaging flanges 9 and 10 for the accommodation of the reduced sized rails.

By referring to Fig. 11 it will be seen that a slightly modified form of a base plate has been provided wherein the plate 19 has a very wide slot 20 and a transversely extending slot 7'. This plate 19 is further provided with openings 2' through which the spikes may be passed when driven into the ties, so as to positively retain the plate in its correct position upon the ties. In other words, this plate 19 is formed similar to the preferred form of the plate as disclosed in Fig. 5 with the exception that the reinforcing strip is removed. However, by the removal of this strip 6 it will be seen that the anchor flanges 12 of the tread plates may be more readily passed into the slot 20 when the device is being assembled. It is, of course, understood that the space 13 formed between the anchor flanges 12 of the tread plates 8 is sufficient to accommodate the breadth of the reinforcing strip, when the anchor flanges 12 are carried within the 110 slot 7.

From the foregoing description it will be seen that a very efficient railroad rail holder has been provided, wherein the base plate is first positioned upon a tie, after which a pair of tread plates are positioned in engagement with the base plate and are positively retained in their correct positions by means of the anchor flanges which will fit within the slots formed on the base plate. The rail 125

then being placed upon the tread plates is further anchored in position by means of the spikes which pass through the openings formed in the base plate for retaining the 5 several elements in their correct positions, and thus prevent the accidental displacement of the plates or the rail. By the construction as hereinbefore set forth it will be seen that the rail will be held from creeping 10 or springing, whereby the rail will also be retained in its correct position by means of the rail engaging flanges of the tread plates.

What is claimed is:

1. In a railroad rail holder of the class described, the combination of a base plate, said base plate provided with openings adjacent its corners, said base plate provided with depending pointed spurs extending from said openings, each of said spurs extending at right 20 angles to its two adjacent spurs, whereby all of the spurs when driven into a tie will take up the strain of retaining the plate in a set position, two of the spurs taking up the strain upon their edge portions so as to prevent 25 their being bent, and means carried upon said base plate for engaging a rail and retaining the same in a set position.

2. In a railroad rail holder of the class described, the combination of a base plate, said base plate being provided with openings adjacent its corners, said base plate provided with depending pointed spurs extending from said openings, each of said spurs extending at right angles to its two adjacent spurs, whereby all of the spurs when driven into a tie will take up the strain of retaining the plate in a set position, two of the spurs taking up the strain upon their edge portions so as to prevent their being 35 bent or injured, and tread plates adjustably mounted upon said base plate for engaging a rail for retaining the rail in a set position.

3. In a railroad rail holder of the class described, the combination of a base plate, means for anchoring said base plate upon a tie, said base plate provided with slots formed therein and extending at right angles to each other, tread plates positioned upon said base plate, said tread plates provided with a plurality of depending anchor flanges formed upon their side edges, said anchor flanges being adapted to fit within a selected slot, whereby said tread plates will be retained in their correct positions 55 upon said base plates and extending parallel to each other, rail engaging flanges

formed upon the remaining side edges of said plates, said tread plates being adapted to carry a rail, whereby said rail engaging flanges will engage the base of the rail adjacent its side portions for holding the rail against lateral movement. 60

4. In a railroad rail holder of the class described, the combination of a base plate, means for retaining said plate in a set position upon a tie, said plate being provided with a pair of elongated slots, thereby forming a reinforcing strip between said slots, said plate provided with an enlarged slot formed therein at right angles to said parallel slots and intersecting the same adjacent their central portions, tread plates positioned upon said base plate, a plurality of anchor flanges formed upon the side edges of said tread plates, the anchor flanges of 70 each tread plate being formed at a distance apart, said anchor flanges being adapted to fit within said parallel slots when so desired to accommodate a large rail and to engage each other and fit within said last-mentioned 75 slot for accommodating a smaller rail, the space between said anchor flanges being sufficient to accommodate the breadth of said reinforcing strip, and means formed upon the remaining side edges of said tread plates 80 for holding a rail in engagement with said tread plates and preventing lateral movement. 85

5. In a railroad rail holder of the class described, the combination of a base plate, 90 said base plate provided with openings adjacent its corners, tread plates positioned upon said base plate, means for retaining said tread plates in an adjusted set position upon said base plate, a plurality of rail engaging flanges formed upon the side edges of said tread plates, the flanges upon each of said tread plates being formed at distances apart thereby forming an open space, the open space of said tread plates registering 100 with the openings formed in said base plate, said tread plates being adapted to support a rail, whereby said rail engaging flanges will hold the rail against lateral movement, and the open space in said tread plates and the 105 openings of said base plate being adapted to accommodate spikes for holding the plates in engagement with each other.

In testimony whereof I hereunto affix my signature.

JENNINGS E. FOGLE.
